UNITED STATES PATENT OFFICE.

HIGGINS L. GOODLOE, OF MARSHALL, MISSOURI.

CRAVAT-SHIELD.

1,109,748.

Specification of Letters Patent.

Patented Sept. 8, 1914.

Application filed November 22, 1911. Serial No. 661,823.

To all whom it may concern:

Be it known that I, HIGGINS L. GOODLOE, a citizen of the United States, residing at Marshall, in the county of Saline and State 5 of Missouri, have invented a new and useful Cravat-Shield, of which the following is a specification.

This invention aims to provide a holder upon which a four-in-hand tie may be fashioned, the construction being such that the tie will not move readily with respect to the holder, novel means being provided for preventing a lateral movement of the tie and button engaging grip, the construction being such that the grip may be engaged 10 readily by the fingers of the operator.

In the drawings: Figure 1 shows the invention in perspective; Fig. 2 is a rear elevation; Fig. 3 is a cross section; Fig. 4 is a 15 longitudinal section; Fig. 5 is a perspective of the grip.

The tie holder herein disclosed comprises a body 1 of approximately T-shape and including a shank 2 and laterally extended 20 arms 3, the lower end of the shank 2 being forwardly extended to form a tie supporting prong 4, the shank 2 having a longitudinal rib 5 alined with the prong 4 and coöperating 25 with the prong to prevent the tie from sliding laterally. A tie engaging and button 30 engaging grip 6 is pivoted to the shank 2, the shank having in its rear, two sets 7—7

and 8—8 of opposed, approaching lips which coöperate with the grip 6 to prevent lateral movement of the grip, the sets of lips being 35 spaced apart longitudinally of the shank, as shown at 9, to permit the fingers of the operator to engage the grip 6.

Having thus described the invention, what is claimed is:—

A tie holder comprising a body of approximate T-shape and including a shank and laterally extended arms, the lower end of the shank being forwardly extended to form a tie supporting prong, the shank having a longitudinal rib alined with the prong and coöperating with the prong to prevent the tie from sliding laterally; and a tie engaging and button engaging grip pivoted to the shank, the shank having in its rear, two sets of opposed, approaching lips coöperating with the grip to prevent the lateral movement thereof, the sets of lips being spaced apart longitudinally of the shank to permit the fingers of the operator to engage 40 the grip. 45 50 55

In testimony that I claim the foregoing as my own, I have hereto affixed my signature in the presence of two witnesses.

HIGGINS L. GOODLOE
